VALVE FOR STEAMING DEVICES FOR
PRESSING MACHINES

Ernest Davis and Albert Kagi, Syracuse, N. Y.,
assignors to The Prosperity Company Inc.,
Syracuse, N. Y., a corporation of New York

Application July 14, 1930. Serial No. 467,751

7 Claims. (Cl. 251—134)

This invention relates to steaming devices for pressing machines and particularly to valve means for controlling the flow of steam through a pressing element.

5 It has become universal practice in the pressing of garments to blow steam over such garments before pressing them. It is highly undesirable, however, when so steaming a garment, to have drops of water which are the result of 10 condensation in the steam line, blow onto the garment.

The principal object of this invention is to devise a steaming device for pressing machines by which steam may be blown over a garment prior 15 to pressing and to devise means which will prevent such steam from containing condensate.

A further object of the invention is to provide a steaming valve so constructed that any steam condensing in the valve, or steam conduit leading 20 to the valve will drain away from the steaming valve and avoid the danger of blowing condensate against a garment during the steaming operation.

A further object of the invention is to provide 25 a particularly simple and efficient steam valve.

Other objects and advantages of the invention will be pointed out and will become apparent as the description proceeds.

The invention consists in the novel features 30 and in the combinations and constructions hereinabove set forth and claimed.

In describing this invention reference is had to the accompanying drawing in which like characters designate corresponding parts in all the 35 views.

Figure 1 is a fragmentary top plan view of a pressing element showing our improved steaming valve applied thereto; the steaming valve being shown partly in section.

40 Figure 2 is a section along the line 2—2 of Figure 1.

Figure 3 is a section along the line 3—3 of Figure 2.

In its preferred embodiment our invention includes a valve casing 10 mounted on a pressing element or head 11 which is formed with a heating chamber 12 to which steam is supplied from any suitable source, not shown. The pressing head 11 is also provided with a steaming chamber 13 from which steam blows through orifices 15 in the pressing face 16 for the purpose of steaming a garment.

A conduit 17 from the heating chamber 12 and 55 a conduit 18 from the steaming chamber 13 are

provided through the top of the pressing head 11.

The valve casing 10 contains an inlet chamber 20 and outlet chamber 21 which are separated by a partition 22. The partition 22 is formed 60 with a conduit 23 therein for establishing communication between the chambers 20 and 21. A valve seat 25 is provided at one end of the conduit 23, this valve seat being raised from the bottom of the chamber 20 so as to prevent condensate 65 from flowing into the conduit 23.

An inlet conduit 28 is provided in the valve casing 10. This conduit 28 communicates at one end with the conduit 17. At its upper end the conduit 28 enters the chamber 20 through the 70 bottom of the side wall thereof and all condensate in the chamber 20 will drain into the conduit 28. As the conduit 28 approaches the chamber 20 the cross-sectional area of the conduit 28 becomes greater thus reducing the velocity of the 75 steam and permitting a more ready flow of condensate back to the conduit 28.

A valve 30 is mounted in the valve casing 10. This valve 30 is provided with a valve stem 31, 80 slidably mounted in the conduit 23, and provided with slots 33 which permit steam to flow from the chamber 20 into the chamber 21 when the valve 30 is not in contact with the seat 25.

The valve 30 is normally held against the seat 25 by a spring 35 thus preventing the flow of 85 steam from the chamber 20 into the chamber 21.

The valve 30 is opened, against the tension of the spring 35, by a lever 38 which contacts with the valve stem 31 at the lower end thereof. The lever 38 is secured to a shaft 40 which is mounted 90 in the valve casing 10. One end of the shaft 40 extends through the side of the valve casing 10 and has a handle 41 mounted thereon by means of which the shaft 40 may be rotated to operate the valve 30. A suitable packing gland 45 may be 95 provided on the side of the valve casing 10 to prevent the escape of steam around the shaft 40.

In operation, the heating chamber 12 will be full of steam at all times. The chamber 20 of the valve casing 10 is at all times in direct communication, through the conduits 28 and 17, with the heating chamber 12. Any condensation which forms in the chamber 20 will drain by gravity back through the conduits 28 and 17 into the heating chamber 12. The valve 30 is normally 100 closed position and prevents steam from escaping from the chamber 20 of the valve casing. When the operator wishes to steam a garment, he depresses the handle 41 to rock the shaft 40 and move the lever 38 through sufficient angle to open 105 110

the valve 30. When the valve 30 is open steam will flow from the chamber 20 through the slots 33 in the valve stem 31 into the chamber 21 from which it will be blown through the orifices 15 in the pressing face 16 of the pressing head. When the operator releases the handle 41 the spring 35 will restore the parts to their normal position.

From the above description it will be apparent that we have provided a particularly simple and efficient steaming device for pressing machines which prevents condensate from being blown over a garment during the steaming process.

Various changes and modifications may be made in the embodiment illustrated without departing from the spirit of the invention as set forth in the appended claims.

What we claim is:

1. A valve for a steaming device including a valve casing having a chamber therein and a steam inlet conduit communicating with the chamber at a low point through which all condensate in the chamber will drain; an exhaust conduit for the chamber; a valve seat around the exhaust conduit and located above the bottom of the chamber; and a valve in the chamber disposed to operate on said valve seat.

2. A valve for a steaming device including a valve casing having a chamber therein and a steam inlet conduit entering said chamber at the bottom of said chamber and at a point to which all condensate in said chamber will drain; said chamber also having a second conduit in the bottom thereof for the exhaust of steam from the chamber; a valve seat raised from the bottom wall of the chamber to prevent condensate from flowing into the second conduit; and a valve for engaging said valve seat.

3. A valve for a steaming device including a casing having a chamber therein, an exhaust conduit in the bottom of the chamber and an inlet conduit at the bottom and adjacent the side wall of the chamber and at a point to which all condensate will drain, a valve seat around the exhaust conduit and raised from the bottom of the chamber to prevent the flow of condensate into the exhaust conduit; a valve having a part slideable in the exhaust conduit; means for normally holding the valve against the valve seat to close the exhaust conduit; and means for operating the valve to open the exhaust conduit.

4. A valve for a steaming device including a casing having a chamber therein, an outlet conduit in the bottom of the chamber and an inlet

conduit at the bottom and adjacent the side wall of the chamber and at a point to which all condensate will drain; a valve seat around the outlet conduit and raised from the bottom of the chamber to prevent the flow of condensate into the outlet conduit; a valve having a stem slidably mounted in the outlet conduit and means for operating the valve to move the same into and out of contact with the valve seat.

5. A valve for a steaming device including a casing having a chamber therein, an outlet conduit in the bottom of the chamber and an inlet conduit at the bottom and adjacent the side wall of the chamber and at a point to which all condensate will drain; the inlet conduit being of increasing cross-sectional area as it approaches the chamber; a valve seat around the outlet conduit; a valve; and means for operating the valve into and out of contact with the valve seat to close and open said outlet conduit.

6. A valve for a steaming device including a casing having a chamber therein, an outlet conduit in the bottom of the chamber and an inlet conduit at the bottom and adjacent the side wall of the chamber and at a point to which all condensate will drain, the inlet conduit being of increasing cross-sectional area as it approaches the chamber; a valve seat around the outlet conduit and raised from the bottom of the chamber to prevent the flow of condensate into the outlet conduit; a valve having a part slideable in the outlet conduit; means for normally holding the valve against the valve seat to close the outlet conduit; and means for operating the valve to open the outlet conduit.

7. A valve for a steaming device for pressing machine heads of the type having a heating chamber and a steaming chamber for steaming a garment, including a valve casing having a valve chamber and an inlet conduit for communicating with the heating chamber of the press head and entering the valve chamber at a low point through which conduit all condensate will drain; said valve chamber also being provided with an outlet conduit for communicating with the steaming chamber of the press head; a valve seat around said outlet conduit and located above the bottom of said valve chamber; a valve in said valve chamber; and means for operating the valve into and out of contact with said valve seat to close and open the outlet conduit.
